CLAIM

The ornamental design for an adapter as shown and described.

DESCRIPTION

FIG. 1 is perspective view of an adapter showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is another perspective view thereof, shown in an unfolded state of use;

FIG. 10 is a partial enlarged view of portion 10 in FIG. 2; and,

FIG. 11 is a partial enlarged view of portion 11 in FIG. 9. The dot-dash broken lines depict reference to and extent of the enlargements and form no part of the claim. All other broken lines in the drawings depict portions of the adapter that form no part of the claimed design.
